CARTON

John E. Walsh, Chicago, Ill., assignor to Self-Locking Carton Co., Chicago, Ill., a corporation of Illinois

Application September 17, 1937, Serial No. 164,303

2 Claims. (Cl. 229—29)

The present invention relates to an improved type of egg carton and has as a particular object the provision of a cushion style carton in which an effective protection may be afforded for 5 fragile articles carried in the carton without the suspension of the bottom of the bottom member in upwardly raised position by engagement thereof with the longitudinal partition or cross walls.

An additional object of the invention is to provide an egg carton of the type described in which a cushion bottom is provided by sloping the bottom sections downwardly and inwardly from the front and rear walls to provide the carton with a bottom section of V-shape, the outer walls being 10 balanced by extending down to the lower portion of the carton and being joined by a flat bottom section.

Still another object of the invention is the construction of an easily erected container having a 15 separate longitudinal partition or centerboard and a double bottom, the inner bottom being inwardly and downwardly sloping.

These and other objects will be observed upon a 20 consideration of the following specification and by reference to the accompanying drawing, in which

Fig. 1 is a top view of a carton constructed in accordance with the invention, the cover of the 25 carton being shown in open position;

Fig. 2 is an end view of the carton shown in Fig. 1, with the cover closed;

Fig. 3 shows the separate longitudinal partition used in the carton of Figs. 1 and 2; and

Fig. 4 is a view of the blank from which the 30 carton shown in Figs. 1 and 2 is constructed.

As shown in Figs. 1 to 3, the carton is constructed by cutting, scoring and folding a single blank of paperboard to form a cover locking strip 10 having hook portions 11, a cover 12, a rear wall

13, an outer bottom section 14, a front wall 15, cross partitions 16 hinged to the front wall by means of hinge members 17, an inner rear wall 18 hinged to the opposite side of the cross partitions by means of the hinge members 19, a rear

inner bottom section 20, a front inner bottom section 21 and a marginal strip 22 attached to the latter. The inner front bottom section 21 is cut away to provide a series of tabs 23 which remain on the strip 22 when the carton is erected, as

50 will be seen in Fig. 2.

In the construction of the carton the blank is cut and scored and in assembly the inner rear wall 18 is folded over and glued to the outer rear wall 13, the bottom sections being folded inwardly 55 of the carton with the strip 22 lying loosely ad-

jacent the front wall 15. This relation will be seen from an observation of Fig. 2. In collapsed condition the cross partitions are in the horizontal position shown in Fig. 3. The ends of the cross partitions are cut away so that they do not extend downwardly as far as the inner bottom wall. Adjacent one end of the carton the cross partitions preferably are of the "split cell" type in which the material between adjacent longitudinally spaced hinges is used to provide two 10 adjacent oppositely directed cross partitions 24, these partitions being of less length than the remainder of the partitions, as will be seen in Fig. 2.

To set up the carton the longitudinal partition 15 shown in Fig. 3 is pressed into engagement with the horizontally extending cross partitions, thereby rotating the cross partitions into vertical position. The hooks 26 on the longitudinal partition 25 are engaged beneath the cross partitions to 20 maintain the longitudinal partition in engagement therewith.

The carton may be collapsed along the score lines between the hinge portions 17 and the front wall. In this case the bottom sections and the strip 22 lie in a plane along the outer bottom section and the front wall. The strip 22 will project along the front wall to a point adjacent the upper portion of the latter, due to the greater length of the inner bottom sections as compared 30 with the outer bottom sections. The carton also may be collapsed along the score lines between the strip 22 and the front inner bottom member 21 also may be collapsed along the lower front wall and the score line between the inner rear 35 wall 18 and the hinges 19. In this case the strip 22 is folded over adjacent the front section 21 and the tabs 23 rest adjacent the outer bottom section.

It will be noted that the continuous inner bottom wall affords a cushion for eggs placed in the carton and extends downwardly and inwardly. Cushion bottom cartons having a continuous bottom wall heretofore have extended upwardly and inwardly in substantially inverted V-shape. The 45 upwardly raised central portion of these previous cushion cartons are suspended by engagement with cross partitions or with the longitudinal partition. By sloping the inner bottom section downwardly and inwardly no such suspension means 50 are necessary, it being satisfactory simply to provide the tabs 23 for bracing the loose outer end of the inner bottom section. The longitudinal partition extends downwardly the complete height of the carton and upwardly to the top of the car- 55

ton, thereby affording substantial bracing effect which helps materially to prevent breakage of eggs.

An advantage of this type of carton is that it 5 may be erected with extreme rapidity by hand. In erection a collapsed carton is grasped in one hand of the operator and the walls are squared. Thereafter, the longitudinal partition is thrust 10 downwardly into engagement with the cross partitions, this latter operation being particularly easy in view of the short cross partitions and the downwardly and inwardly extending shape of the inner bottom wall.

It will be noted that the outer bottom wall is 15 flat and provides added protection for the eggs. The cartons may be stacked without collapsing the carton or endangering the bottom.

It will be recognized that many changes may 20 be made in the construction described specifically herein without departing from the scope of the invention as defined in the appended claims.

I claim:

1. A carton of the type described, comprising a 25 blank cut, scored and folded to form a rear wall, a continuous flat bottom, a front wall, cross parti-

tions hinged to said front wall, an inner rear wall hinged to said cross partitions, an inner rear bottom section extending downwardly and inwardly adjacent the center of the carton, an inner 5 front bottom section integral with said inner rear bottom section and extending outwardly and upwardly adjacent the front wall, a marginal strip connected to said inner front bottom section, and tabs struck from the material of said inner bottom section extending downwardly from 10 said marginal strip.

2. A carton of the type described, comprising a blank cut, scored and folded to form a rear wall, a continuous flat bottom, a front wall, cross partitions hinged to said front wall, an inner rear wall 15 hinged to said cross partitions, an inner rear bottom section extending downwardly and inwardly adjacent the center of the carton, an inner front bottom section integral with said inner rear bottom section and extending outwardly and upwardly adjacent the front wall, and a marginal strip connected to said inner front bottom section. 20

JOHN E. WALSH.
